UNITED STATES PATENT OFFICE.

LUTHER D. LOVEKIN, OF PHILADELPHIA, PENNSYLVANIA.

BOILER.

1,119,026.

Specification of Letters Patent. Patented Dec. 1, 1914.

Annexation filed December 24, 1918. Serial No. 802,569.

To all whom it may concern:

Be it known that I, LUTHER D. LOVEKIN, a citizen of the United States of America, residing in the city and county of Philadelphia, in the State of Pennsylvania, have invented certain new and useful Improvements in Boilers, of which the following is a true and exact description, reference being had to the accompanying drawings, 10 which form a part thereof.

My present invention relates to steam generating boilers, and has for its object to provide a horizontal cylindrical boiler, such as the Scotch type of marine boiler, 15 with suitable internal provisions for drying and superheating the steam issuing from the boiler.

In the practical use of marine boilers of the Scotch type and other horizontal cylindrical boilers, as heretofore constructed, the steam issuing from the boiler frequently contains as high as five per cent. of moisture, and with this type of boiler the issuing steam is regarded as "commercially dry" when it contains as little as two and one-half per cent. of moisture. The reason for this high percentage of moisture in steam issuing from a boiler of the kind referred to is due to the violent ebullition 25 set up in the neighborhood of the combustion chamber and the hotter parts of the boiler tubes, which causes bubbles of steam to rise with such rapidity as to keep the water surface continually broken. These 30 bubbles of steam carry up with them from the broken water surface small particles of water which are held in mechanical suspension in the steam. Steam containing as much as two and one-half per cent. of moisture should not be used in engine cylinders or turbines, and moisture present in appreciably smaller percentages produces water hammering and other troubles, and is a frequent source of considerable damage. 35 Heretofore it has been frequently proposed to provide some sort of steam separator within the boiler to reduce the amount of moisture carried by the steam leaving the boiler, but these separating devices whether 40 in the form of the common dry pipe perforated on top, or in more complex form, are all open to the objection that they tend to lower the pressure at which the steam leaves the boiler, and in practice are not 45 effective in securing the delivery of dry

steam. It is possible, of course, to dry and to superheat the steam by means of external drying and superheating devices, and this practice is generally followed, but such external devices are cumbersome and 50 more or less expensive, and generally inefficient and undesirable.

In constructing a boiler in accordance with the present invention, I place a series of heating tubes within the boiler shell 65 above the water level and extending between the end walls thereof, and pass a portion of the products of combustion through these tubes, and I arrange baffle provisions so that the steam issuing from 70 the steam space of the boiler proper will pass through and along the spaces between these tubes under such conditions that it will be effectually dried and superheated. When the tubes are properly arranged and 75 proportioned and suitable provisions are made for directing the flow of the steam relative to the flow of the hot gases in the tubes, as hereinafter described in detail, I can give the steam from fifty to one hundred 80 degrees of superheat when this is desirable.

The various novel features of construction and arrangement which characterize my invention are pointed out with particularity in the claims annexed to and forming a part of this specification. For a better understanding of the invention, however, and of the advantages possessed by it, reference should be had to the accompanying drawings and descriptive matter, 85 in which I have illustrated and described forms in which my invention may be embodied.

Of the drawings: Figure 1 is a sectional elevation of one form of boiler constructed 90 in accordance with the present invention, the section being taken on the line 1—1 of Fig. 3; Fig. 2 is a longitudinal section of a portion of the boiler shown in Fig. 1; Fig. 3 is a section taken partly on the line 3—3 and 95 partly on the line 3¹—3¹ of Fig. 1; Fig. 4 is a section taken on the line 4—4 of Fig. 3; and Fig. 5 is a sectional elevation of another form of boiler constructed in accordance 100 with the present invention.

In the drawings, and referring first to the construction shown in Figs. 1 and 3, A represents the wall of the cylindrical boiler shell, and B and C the front and rear end walls, respectively. Within the boiler shell 110

and separated from the front and rear ends thereof though much nearer the latter than the former are located the usual combustion chamber, or chambers. As shown in Figs. 1 and 3, there are three of these chambers, one central chamber E, and two side chambers E'. Those familiar with this type of boiler will understand, however, that the number of combustion chambers provided depends upon the operating conditions and to the size and to some extent the preferences of the boiler. The front end wall B of the boiler shell and the front end of each of the combustion chambers E and E' is connected by the wall of a corresponding tubular furnace chamber D. The wall of each of the furnace chambers D is in the form of a corrugated cylinder. Above and at the sides of each of the furnace chambers D are respective turn flues F which extend between the front ends of the combusticu chambers and the front end wall B of the boiler. The flues F serve to convey products of combustion which enter the combustion chambers E and E' from the furnace chambers D to the smoke box Q into which the flues F discharge at the front end of the boiler.

The construction shown in Figs. 1 and 2 as hereinbefore described in detail possesses nothing now novel with me, but on the contrary is a typical example of a marine boiler of the Scotch type.

Each of the combustion chambers E and E' is connected at its upper end to a chamber formed in a casing M attached to the rear end of the boiler proper by a number of short tubes L which extend between the rear end walls of the combustion chambers and the rear end wall C of the boiler. The hot gases passing from the combustion chamber into the casing M are conveyed from the latter to the smoke box Q through a group of tubes P which extend through the interior of the boiler between the end walls B and C near the top of the boiler shell. The casing M which may be formed of sheet iron lined with refractory material is preferably formed with clean out doors M' and M''. Preferably also a damper M³ is provided by which the flow of hot gases through the casing may be regulated and cut off.

O represents stay bolts connecting the end walls B and C of the boiler below the level of the tubes P and above the level of the combustion chamber. As shown, the casing M is shaped to provide an air space N, open to the atmosphere at its ends, into which the rear ends of the stay bolts O project and are thereby protected from the high temperature prevailing within the casing M.

It is to be noted that the tubes P perform the purpose of and take the place of stay bolts similar to the bolts O which otherwise would have to be employed to tie the upper portions of the end walls B and C together.

Similarly the short tubes L take the place of stay bolts such as the stay bolts O A beneath them which would otherwise be required to tie the rear end walls of the combustion chamber to the rear end wall of the boiler proper.

To insure a sufficiently prolonged contact of the steam issuing from the boiler with the tubes P, under conditions which will insure the drying of the steam and its superheating, I have provided a novel baffle arrangement.

This baffle arrangement consists of two plates, S and S', which are attached at their upper edges to the boiler shell at opposite sides to the bank of tubes P and converge toward one another as they project in from the boiler shell. Between the plates S and S' are plates SA and SA' parallel respectively to the plates S and S'. The four plates S, S', SA and SA' are connected to

and support a horizontal wall T. The latter thus forms the bottom wall, and the plates S and S' the side walls of a trough-shaped casing inclosing a steam drying and superheating space, which is divided up into a central chamber U and two side chambers U' by the partitions formed by the plates SA and SA'.

The plates S and S' extend the length of the boiler, but the plates SA and SA' do not, being spaced away from the tube sheet B, and thereby connecting the chambers U, U' and U', as shown best in Fig. 4. Steam is admitted to the chambers U' through the ports S¹⁰ formed in the walls S and S'.

As shown there is a longitudinal row of these ports formed in each of the walls S and S' adjacent the lower edge of the latter and extending from the tube sheets C for rather more than half the length of the boiler. As shown these ports S¹⁰ are formed by making three sided cuts in the plates S and S', and then pushing each tongue S¹¹ thus formed outward from the plane of the plate from which it is cut, as shown in Fig. 3. The tongues S¹¹ serve to prevent water which may run up along the curved wall of the boiler shell from dashing into the chambers U' through the ports S¹⁰.

The drying and superheating effect may be regulated somewhat by manipulating the damper M'. These ports, which form the only communicating passages between the steam drying and superheating space and the steam generating portion of the boiler proper, are thus effectually shielded against the introduction of water therethrough, which is a matter of considerable importance, especially in the case of marine boilers.

The steam passing into the chambers U' through the ports S¹⁰ travels longitudinally of the tubes P passing through said chambers to the end of the boiler at which the tube sheet B is located, and then passes into the central chamber U. Transverse

baffling walls U², U³, U⁴ and U⁵ are em-

ployed to compel the steam to travel more or less completely across, as well, the tubes P several times on its way to the steam outlet R of the boiler, which opens from the 5 chamber U adjacent the tube sheet C. The flow of steam through the chamber U longitudinally of the tubes, is opposite in direction to the flow of the hot gases within the tubes. The counter-current flow of hot gases and steam thus obtained is of great importance 10 in securing not only a high degree of superheat but also a steady superheating effect. Under ordinary conditions the steam is effectually dried as it passes through the 15 outer chambers U'. Water separating from the steam and collecting in the bottoms of the chambers U and U' is discharged into the steam generating portion proper of the boiler through the pipe V, the lower end of 20 which is located below the water level of the boiler. The amount of superheat imparted to the steam will of course depend upon the number, size and arrangement of the tubes P, and the volume and temperature 25 of the hot gases passing through the tubes.

In Fig. 5 I have shown my improved steam drying and superheating provisions applied to a boiler of what may be called the combined Scotch and gunboat type, differing from that shown in Figs. 1 to 4 in that the combustion chamber EA or each of them if there be more than one is not only connected to the front end of the boiler by one or more 30 furnace chambers D and return flues F, but is also connected to the rear end of the boiler by direct flues G which are shorter and smaller in diameter than the flues F and discharge into a smoke box QA connected to the rear end of the boiler. The smoke box QA and the smoke box Q may well be connected to the same chimney or draft pipe. In Fig. 5 the combustion chamber EA or 35 each of them if there be more than one is connected adjacent its upper end by tubes LA to a chambered casing MA. The tubes LA and casing MA correspond generally to the tubes L and chamber M of the construction first described. The tubes P leading from the chamber MA to the front smoke box Q perform the same function as in the 40 construction first described, and the boiler shown in Fig. 5 comprises partition and baffle provisions S, S', SA, SA', U², U³, U⁴, and U⁵, similar to those shown in Figs. 1 to 4.

While in accordance with the provisions of the statutes, I have illustrated and described the best forms of my invention now known to me, it will be apparent to those skilled in the art that changes may be made in the forms of the apparatus disclosed without departing from the spirit of my invention, and that under some conditions certain 45 features of my invention may be used without a corresponding use of other features.

Having now described my invention, what I claim as new and desire to secure by Letters Patent, is:

1. The combination in a horizontal cylindrical boiler, comprising an external boiler shell with a steam outlet therefrom an internal combustion chamber and the usual submerged flues each leading from said combustion chamber to an end wall of the boiler, of tubes located within said boiler shell above the water level in the boiler and extending between said end walls, means for causing hot gases discharged by some of said flues at one end of the boiler to be conveyed through said tubes to the opposite end of the boiler and provisions for causing the steam generated in said boiler to flow along and across said tubes in passing to said steam outlet.

2. The combination in a horizontal cylindrical boiler, comprising an external boiler shell with a steam outlet therefrom at one end of the boiler, an internal combustion chamber, the usual submerged flues leading from said combustion chamber to both end walls of the boiler, of tubes located within said boiler shell above the water level in the boiler and extending between said end walls, means for causing the hot gases discharged by some of said flues at said one end of the boiler to be conveyed through said tubes to the opposite end of the boiler, and provisions for causing the steam generated in said boiler to flow along said tubes from said opposite end of the boiler to said steam outlet.

3. The combination in a horizontal cylindrical boiler, comprising an external boiler shell with a steam outlet therefrom, an internal combustion chamber and the usual submerged flues each leading from said combustion chamber to an end wall of the boiler, of tubes located within said boiler shell above the water level in the boiler and extending between said end walls, means for causing hot gases discharged by some of said flues at one end of the boiler to be conveyed through said tubes to the opposite end of the boiler comprising a chambered casing external of the boiler shell, means for regulating the flow of hot gases through said casing and provisions for causing the steam generated in said boiler to flow along and across said tubes in passing to said steam outlet.

4. The combination in a horizontal cylindrical boiler, comprising an external boiler shell with a steam outlet therefrom, an internal combustion chamber and the usual submerged flues each leading from said combustion chamber to an end wall of the boiler, of tubes located within said boiler shell above the water level in the boiler and extending between said end walls, means for causing hot gases discharged by some of said

- flues at one end of the boiler to be conveyed through said tubes to the opposite end of the boiler, said means comprising a chambered casing attached to the end wall of the 5 boiler in register with said tube and flue ends and formed with an offset portion whereby a portion of the outer surface of the end wall between the levels of said tubes and flues is exposed, stay bolts connecting the said exposed end wall portion to the opposite end wall of the boiler and provisions for causing the steam generated in said boiler to flow along and across said tubes in passing to said steam outlet.
- 10 5. In a horizontal cylindrical boiler, the combination with the boiler shell having a steam outlet and the usual submerged heating flues and other submerged heating surfaces, of a casing located within the boiler shell and uniting with the latter to form a steam drying and superheating chamber located above the water level in the boiler and extending from one end of the latter to the other, partitions within said casing 20 dividing said space up into longitudinal chambers which communicate with one another adjacent one end of the boiler, the said steam outlet leading from one of said chambers adjacent the opposite end of the 25 boiler, and the said casing being formed with ports connecting the other chamber or chambers to the interior of the boiler proper at a distance from the first mentioned boiler end, tubes located within the different chambers and extending from one end of the boiler to the other and provisions for passing hot gases through said tubes.
- 30 6. In a horizontal cylindrical boiler, the combination with the boiler shell having a steam outlet and the usual submerged heating flues and other submerged heating surfaces, of a casing located within the boiler shell uniting with the latter to form a steam drying and superheating chamber located 35 above the water level in the boiler and extending from one end of the latter to the other, partitions within said casing dividing said space up into a central chamber and two side chambers extending longitudinally 40 of the boiler and in communication with one another at one end of the boiler, the steam outlet opening from said central chamber at the opposite end of the boiler and said side chambers being formed with ports in their outer walls located at a distance from the first mentioned boiler end, tubes located within the different chambers and extending from one end of the boiler to the other and provisions for passing hot gases through 45 said tubes.
- 50 7. In a horizontal cylindrical boiler, the combination with the boiler shell having a steam inlet adjacent one end, the usual submerged heating flues and other submerged heating surfaces, of a casing located within 55 the boiler shell and uniting with the latter to form a steam drying and superheating chamber located above the water level in the boiler and extending from one end of the boiler to the other, and having partitions within said casing dividing said space up into a central chamber and two side chambers extending longitudinally of the boiler, said central chamber being in communication with said steam outlet at the one end of the boiler and in communication with said side chambers at the opposite end of the boiler and said side chambers being formed with ports in their outer walls located at a distance from the end of the boiler at which the steam outlet is located, tubes passing through the different chambers from one end of the boiler to the other, and means for causing hot gases to flow through said tubes from said one end to said opposite end of the boiler.
- 60 8. In a horizontal cylindrical boiler, the combination with the boiler shell having a steam outlet and the usual submerged heating flues and other submerged heating surfaces, of a steam drying and superheating space located within the boiler shell and above the water level therein and comprising a central chamber and two side chambers and formed by four plates extending longitudinally of the boiler, and secured at their upper edges to the top wall of the latter, and means for closing the lower edges of the chambers thus formed between said plates, said chambers being in communication with one another adjacent one end of the boiler and said steam outlet opening at the opposite end of the boiler from said central chamber, the outer pair of plates having ports formed through them to admit steam into the outer chambers, tubes located within the different chambers and extending from one end of the boiler to the other and provisions for passing hot gases through 65 said tubes.
- 70 9. In a horizontal cylindrical boiler, the combination with the boiler shell having a steam outlet and the usual submerged heating flues and other submerged heating surfaces, of a trough-shaped casing located within the boiler shell and secured at its upper edges to the latter and uniting therewith to form a steam drying and superheating space above the water level in said shell and from which said steam outlet leads, said casing having a series of ports formed in each side wall, hoods carried by said side walls for preventing water running up the side of the boiler shell from splashing through said ports, a set of tubes extending from one end of the boiler to the other through said space, and provisions for passing hot gases through said tubes.
- 75 10. In a horizontal cylindrical boiler, the combination with the boiler shell having a

steam outlet and the usual submerged heating flues and other submerged heating surfaces, of a trough-shaped casing located within the boiler shell and secured at its upper edges to the latter and uniting therewith to form a steam drying and superheating space above the water level in said shell and from which said steam outlet leads, said casing having a series of cuts made in each 10 side wall to form tongues each attached at its upper end to the side wall from which it is cut and being bent outward from the plane of the latter, thereby providing ports in said side walls and hoods preventing the 15 passage of water through said ports, a set of tubes extending from one end of the boiler to the other through said space, and provisions for passing hot gases through said tubes.

20 11. In a horizontal cylindrical boiler the combination with the boiler shell having a steam outlet and the usual submerged heating flues and other submerged heating surfaces, of a steam drying and superheating space located within the boiler shell and above the water level therein and comprising 25 chambers arranged side by side and extending longitudinally of the boiler and formed by plates secured at their upper edges to the top wall of the boiler, and means connecting the lower edges of said 30 plates, tubes extending from one end of the boiler to the other through each of said chambers, and provisions for passing hot gases through said tubes, said steam outlet leading from one of said chambers adjacent 35 one end of the boiler, and said plates being cut away to place said chambers in communication with one another and for admitting 40 steam to said space from the boiler in such 45 manner that the steam entering said space through said ports will flow back and forth longitudinally of said tubes on its way to 50 said steam outlet.

55 12. In a horizontal cylindrical boiler the 45 combination with the boiler shell having a steam outlet and the usual submerged heating flues and other submerged heating surfaces, of a steam drying and superheating space located within the boiler shell and 50 above the water level therein and comprising chambers arranged side by side and extending longitudinally of the boiler and formed by plates secured at their upper 55 edges to the top wall of the boiler, and means connecting the lower edges of said plates, tubes extending from one end of the boiler to the other through each of said 60 chambers, and provisions for passing hot gases through said tubes from one end of the boiler to the other, said steam outlet leading from one of said chambers adjacent one end of the boiler, and said plates being 65 cut away to place said chambers in communication with one another and for admitting 70 steam to said space from the boiler in such manner that the steam entering said space through said ports will flow back and forth longitudinally of said tubes on its way to 75 said steam outlet and in the final portion of its travel along said tubes will move in a direction to that in which the hot gases are flowing through said tubes.
